BY MESNE ASSIGNMENTS, TO THE SYMINGTON COMPANY, A CORPORATION OF
MARYLAND.

DRAFT RIGGING.

Application filed March 30, 1922. Serial No. 548,198.

To all whom it may concern:

Be it known that we, BYERS W. KADEL and PERCY R. DRENNING, citizens of the United States, residing at Baltimore city, 5 in the State of Maryland, have invented certain new and useful Improvements in Draft Rigging; and we do hereby declare the following to be a full, clear, and exact description of the invention, such as will 10 enable others skilled in the art to which it appertains to make and use the same.

This invention relates to draft rigging for railway cars.

The present invention has for an object 15 to provide a vertical key connection between the yoke and coupler and to associate with said key, means adapted to guide the same, said means also acting to guide the yoke and form a front stop for the forward end of 20 the cushioning mechanism.

The invention has for a further object to provide a draft rigging including in combination cooperatively associated front and back stop members connected to the draft 25 sills, the said back stop member acting to guide the rear of the yoke and to limit rearward movement thereof beyond a predetermined position, said front stop member acting to guide the forward end of the yoke 30 and also having a portion adapted to guide the vertical key.

A still further object of the invention is to provide an operable connection including a vertical key, between the yoke and coupler, 35 and means including a supplemental member connected to and bridging the draft sills, said supplemental member acting to guide the vertical key and provided with front and rear supplemental stops with 40 which said key engages upon movement of the key beyond predetermined positions.

A still further object of the invention is to provide an operable connection including a vertical key between the yoke and coupler, 45 means secured to the draft sills for supporting and guiding said key, a portion of the guiding means being detachably connected to said sills, said detachable portion being provided with means for guiding the 50 forward end of the yoke.

The invention further consists in the combination and construction of the several parts hereinafter described and pointed out in the appended claims.

In the drawings in which I have chosen 55 to illustrate an embodiment of the invention and wherein similar reference characters designate corresponding parts in the several views.

Figure 1 is a sectional plan view of the 60 center sills and associated parts of the car under frame showing a draft rigging embodying the invention.

Figure 2 is a central longitudinal sectional view of the construction shown in Figure 1. 65

Figure 3 is a transverse sectional view on the line 3—3 of Figure 2 viewed in the direction of the arrows.

Figure 4 is a similar view on the line 4—4 of Figure 2 viewed in the direction of the 70 arrows.

Figure 5 is a horizontal sectional view on the line 5—5 of Figure 2 with the coupler removed.

Figure 6 is a detail central longitudinal 75 vertical sectional view of the front portion of the draft rigging showing the supplemental member and associated parts connected to the draft sills, the coupler and yoke not being illustrated.

The present invention includes among other things, the center or draft sills 1—1 of the car underframe, a back stop member 2 arranged between and connected to the sills by means of rivets 3, and a front or 85 supplemental member 4 preferably formed of a one-piece or unitary structure and adapted to bridge and be connected to the center sills by rivets 5. Both back stop member 2 and supplemental member 4 are 90 adapted to cooperate with a vertical yoke 6 operatively connected to the coupler 7 by means of a vertical key 8, said supplemental member 4 being designed to guide and limit the movements of the vertical key in either 95 direction beyond a predetermined position, as will be hereinafter described.

The back stop member 2 is preferably formed of one casting and is provided with rear stop lugs 9, an intermediate central 100

flange or web 10 located in the rear of said stop lugs and being provided with a buffing face 11, a central thimble 12, and opposite side walls between which and the aforesaid 5 parts are arranged a series of reinforcing flanges or webs, as shown. The rear stop lugs 9 project forwardly of the yoke and are each formed with a plurality of horizontal reinforcing webs 13, the opposed inner faces of which latter form guides for 10 the rear end of the yoke. In the rear of said stop lugs 9 and centrally thereof is the upright flange 10 provided with the buffing face 11, vertical longitudinally arranged reinforcing webs 14, and horizontally disposed transverse reinforcing webs 15 connecting the said upright flange 10 with the side walls and top and bottom flanges of the casting. The oppositely disposed side walls 15 are indicated by the numeral 16, said walls being formed integral with the top flange 17 and the bottom or floor flange 18 positioned upon the center plate 19. Other reinforcing webs 20 may be arranged to project rearwardly from the central thimble, 25 as shown.

A back stop and center sill tie casting including the forgoing associated parts is particularly adapted for use in connection with 30 various length yokes and cushioning mechanisms, it being obvious that the rear follower of the cushioning mechanism, the latter being conventionally shown by the diagonal dot and dash lines in Figures 1 and 2, 35 would engage the rear stops 9 in receiving buffing strains. The present construction also permits of the use of longer yokes whereby the said yoke is adapted to engage the buffing face 11 when the cushioning 40 mechanism becomes solid and thereby transmit excessive buffing stresses to the center sills, the rearward movement of said yoke being limited by the upright flange 10.

Surrounding the cushioning mechanism is 45 the vertically arranged yoke 6 having its forwardly extending yoke arms 21 increased in thickness, as at 22, to provide an increased bearing area for the vertically arranged coupler connecting key 8. Slots 23 50 are provided in each yoke arm, the forward portion of the side faces of said slots being inclined or tapered and extending rearwardly into relatively wide portions with parallel opposed faces, as shown in Figure 5, thereby providing lateral clearance for 55 the pivotal movement of the coupler key, the key slot in the coupler 7 being adapted to closely embrace the said key.

The vertical coupler key 8 is of a length 60 which provides for its extending above and below the upper and lower faces of the yoke arms, said key being of a length greater than the combined thickness of the yoke and coupler. The projecting portions of the 65 key are adapted to be guided in an opening

formed in the upper supplemental member 4, and a bifurcated portion 24 formed in the guide member 25. The guide member 25 guides the lower end of the key 8, and is detachably connected to the center sills by 70 means of a key 26, said last named key being adapted to pass through an opening formed in the body portion of the guide member 25 and registering openings formed in the brackets or hangers 27 connected to the 75 lower flanges of the center sills. The bifurcated portion of the lower guide member 24 projects forwardly and extends into a transverse support 28 which latter is connected to the lower flanges of the center sills by means 80 of bolts 29. The support 28 forms a bearing surface for the lower edge of the coupler key, said key being guided in the bifurcated portion of the member 24. The opposite faces of the bifurcated or open slotted portion are inclined or tapered in a forwardly direction and terminate in relatively wide portions with parallel opposed faces, said inclined and parallel faces being arranged 85 reversely of the slots 23 provided in the yoke 90 arms 21.

Means for guiding the forward and lower arms of the yoke is provided on the lower guide member 25, said means including a plurality of lugs 30 having guide faces 31 (see Figures 2 and 5). The lugs are formed of a sufficient width to extend between the inner faces of the center sills and the sides of the yoke.

Means for guiding the forward end of the upper arm of the yoke is carried by the supplemental member 4, said means consisting of lugs 32 having guide faces 33. The lugs 32 are of a width equal to the lugs 30 for filling the space between the inner faces of 100 the center sills and the sides of the yoke.

The supplemental member 4 involves the bridge plate section 34 having depending ribbed or reinforced portions 35 adapted to be connected to the inner faces of the center sills by means of rivets 5, said depending portions being further connected or bridged by means of an integral cross member 36 adapted to form a support for the carry iron 37. The forward portion 38 of the member 4 froms a striking casting, as clearly shown 110 in Figure 2. The innermost portions 39 of the ribbed depending sections serve as guides for the yoke, and the vertical faces 40 of said depending sections act as front 115 stops with which the forward follower of the cushioning mechanism engages.

An integral housing 41 is provided in the member 4, said housing having a groove or slot 42 adapted to receive the upper end of 120 the coupler key, and front and rear walls 43 and 44 adapted to form forward and rear supplemental stops for said key upon movement thereof in either direction beyond a 125 predetermined position, the respective edges 130

of said coupler key engaging said stops when the cushioning mechanism becomes solid on either draft or buff. The groove or slot 44 is of greater width than the coupler key so as to permit of the angling of said key on pivotal movement of the coupler.

Another forward stop 45 for the lower front edge of the coupler key is provided on the bridge member 36 connecting the 10 pending sections 35, said stop 45, being vertically alined with the front stop 43 whereby forward movement of said key is arrested beyond a predetermined point. A rear stop 46 is also provided for the lower rear edge 15 of the coupler key upon movement beyond a predetermined position, said rear stop being the end wall of the bifurcated or slotted portion in the detachable lower guide member 24 and being further vertically alined 20 with the rear wall or stop 44 provided on the top bridge portion of the supplemental member.

The supplemental member 4 is strengthened by a series of webs or flanges adapted 25 to directly reinforce the front and rear walls of the housing 41 against which walls the respective edges of the coupler key are designed to abut. A series of radiating webs 47 is provided for the front wall, and a 30 series of similar flanges or webs is provided for the rear wall. Laterally extending webs 48 are provided at the rear of the place sections, one of said webs intersecting the rear wall of the housing, the other of said webs 35 constituting an upturned flange at the rear of the top bridge portion.

The relative association of front and rear stops for the cushioning mechanism arranged within a vertical yoke, and the construction of the supplemental bridge and supporting casting carried by the center sills and adapted to effectively guide and limit the respective forward and rearward movements of the vertical key connecting 45 the yoke and coupler, constitutes a particularly adaptable draft rigging which can be easily installed and economically maintained.

We claim:

50 1. In a draft rigging, the combination with draft sills, of cushioning mechanism, a coupler, a vertically arranged yoke, means for guiding the front end of said yoke, guide means for the rear end of said yoke, said guide means at the rear of the yoke 55 acting to form a stop member therefor upon the movement of the yoke beyond a predetermined position, means connecting said yoke and coupler adapted to permit relative movement therebetween, and means for guiding said connecting means.

2. In a draft rigging, the combination with draft sills, of a cushioning mechanism, a coupler, a vertically arranged yoke, means 60 for guiding the forward end of said yoke,

guide means for the rear end of said yoke, said guide means at the rear of the yoke forming a stop member therefor upon movement of the yoke beyond a predetermined position, means connecting said yoke and 70 coupler adapted to permit relative movement therebetween, and means connected to said draft sills for guiding the means connecting said yoke and coupler.

3. In a draft rigging, the combination 75 with draft sills, of a cushioning mechanism, a coupler, a vertically arranged yoke, means for guiding the forward end of said yoke, guide means for the rear end of said yoke, said guide means at the rear of the yoke 80 providing stop means therefor upon movement of the yoke beyond a predetermined position, means including a vertical key connecting said yoke and coupler, said means being adapted to permit relative movement 85 therebetween, and means extending above and below and connected to said draft sills for guiding said key.

4. In a draft rigging, the combination 90 with draft sills, of a cushioning mechanism, a coupler, a vertically arranged yoke, means for guiding said yoke at the front end thereof, guide means for the rear end of said yoke, said guide means at the rear of the yoke forming a stop adapted to engage the 95 rear of said cushioning mechanism, means connecting said yoke and coupler, said means being adapted to permit relative movement therebetween, and means for guiding said connecting means, said last 100 mentioned means also forming a stop adapted to engage the forward end of said cushioning mechanism.

5. In a draft rigging, the combination 105 with draft sills, of a cushioning mechanism, a coupler, a vertically arranged yoke, means for connecting said yoke and coupler adapted to permit relative movement therebetween, means connected to and bridging said draft sills for guiding said connecting 110 means, said means acting to guide the front end of said yoke, and means connected to said draft sills acting to guide the rear end of said yoke.

6. In a draft rigging, the combination 115 with center sills, of a cushioning mechanism, a coupler, a vertically arranged yoke, a vertical key for connecting said yoke and coupler adapted to permit relative movement therebetween, means carried by the center 120 sills for retaining and guiding said vertical key, said means forming a front stop adapted to engage the forward end of said cushioning mechanism.

7. In a draft rigging, the combination 125 with a cushioning mechanism, of a coupler, a vertically arranged yoke, means for connecting said yoke and coupler adapted to permit relative movement therebetween, and means for guiding said connecting means, 130

- 4
- said last named means being adapted to engage the forward end of said cushioning mechanism.
8. In a draft rigging, the combination with center sills, of a coupler, a vertically arranged yoke, means connecting said yoke and coupler adapted to permit relative movement therebetween, and means extending above and below said center sills and connected thereto, said last named means being adapted to guide said yoke and the means connecting the coupler and yoke. 70
9. In a draft rigging, the combination with center sills, of a coupler, a vertically arranged yoke, means connecting said yoke and coupler adapted to permit relative movement therebetween, and means connected to said center sills for guiding said yoke, said last mentioned means also acting to guide the means connecting said yoke and coupler. 75
10. In a draft rigging, the combination with draft sills, of a coupler, a yoke, a vertical key connecting said yoke and coupler adapted to permit relative movement therebetween, upper and lower members provided on said draft sill for guiding said key, and means for preventing movement of said key either in forward or rearward directions beyond predetermined positions. 80
11. In a draft rigging, the combination with draft sills, of a coupler, a yoke, a vertical key connecting said yoke and coupler adapted to permit relative movement therebetween, and means carried by said draft sills adapted to engage the respective ends of said key for guiding the same, said means acting as a stop for the key when moved in either a forward or rearward direction beyond predetermined points. 85
12. In a draft rigging, the combination with draft sills, of a coupler, a yoke, a vertical key connecting said yoke and coupler adapted to permit relative movement therebetween, and supplemental stop members carried by said draft sills and adapted to limit the forward or rearward movement of said key beyond a predetermined point, said stop members acting to guide said yoke at its forward end. 90
13. In a draft rigging, the combination with center sills, of a coupler, a yoke, a vertical key connecting said coupler and yoke adapted to permit relative movement therebetween, means carried by said center sills and adapted to support said key, and means carried by said center sills for guiding said key, said last mentioned means being adapted to guide said yoke. 95
14. In a draft rigging, the combination with center sills, of a coupler, a yoke, a vertical key connecting said coupler and yoke adapted to permit relative movement therebetween, rigid means carried by said draft sills for supporting said key, means for guiding said key, a portion of said guiding means being detachably connected to said draft sills, said detachable portion being provided with means for guiding the forward end of said yoke. 100
15. In a draft rigging, the combination with center sills, of a coupler, a yoke, a vertically arranged key for operatively connecting said coupler and yoke, and a guide member for said key connected to the center sills, said guide member being provided with forward and rear stops with which the respective edges of the key are adapted to engage upon movement of said key beyond predetermined points in either a forward or rearward direction. 105
16. In a draft rigging, the combination with center sills, of a coupler, a yoke, a vertically arranged key for operatively connecting said coupler and yoke, and a guide member for said key connected to the center sills, said guide member being provided with a plurality of stops for said key and spaced lugs for guiding said yoke. 110
17. In a draft rigging, the combination with center sills, of a coupler, a yoke, a vertically arranged key for operatively connecting said coupler and yoke, and a guide member for said key connected to the center sills, said guide member being provided with spaced vertically aligned front stops for limiting the forward movement of said key beyond a predetermined point. 115
18. In a draft rigging, the combination with center sills, of a coupler, a yoke, a vertically arranged key for operatively connecting said coupler and yoke, and a guide member connected to the top of said center sills, said member having a housing provided with a groove in which the upper end of said key is guided, and formed with front and rear stop walls with which the respective edges of the key are adapted to engage upon movement beyond a predetermined position. 120
19. In a draft rigging, the combination with center sills, of a coupler, a yoke, a vertically arranged key for operatively connecting said coupler and yoke, and guide means connected to the center sills for said key, said means including spaced vertically aligned front and rear stops for the respective edges of both upper and lower ends of said key. 125
20. In a draft rigging, the combination with center sills, of a coupler, a yoke, a vertically arranged key for operatively connecting said coupler and yoke, a guide member connected to the center sills and adapted to guide said key, said guide member being provided with spaced vertically aligned front stops and a single rear stop, and another guide member and rear stop for said key, said last mentioned guide member being detachably connected to the center sills. 130

21. In a draft rigging, a member adapted to be connected to the center sills, said member involving a bridge plate formed with means for guiding a vertical coupler key, 5 depending sections adapted to form guide means for a vertical yoke, and a lower bridge portion uniting said depending sections and serving as a carry iron support.
22. In a draft rigging, a member adapted 10 to be connected to the center sills, said member involving a bridge plate having depending sections adapted to form a stop for the forward end of the cushioning mechanism, and means on said member for guiding a vertical coupler key.
23. In a draft rigging, a member adapted 15 to be connected to the center sills, said member comprising a bridge plate having depending sections adapted to form guides for the front end of a vertical yoke, said depending portions having formed integral therewith an upper forward end forming a 20 striking casting and a lower bridge portion connecting the depending sections, said lower bridge portion forming a support for 25 the carry iron.
24. In draft mechanism, the combination of spaced draft sills, a coupler, yieldable draft means including a yoke, a vertical key connecting said coupler and yoke, said key 30 being immovably secured to one and longitudinally movable with respect to the other during a relative longitudinal movement between said coupler and yoke, front and rear stop members secured to said draft sills, 35 followers engageable with said stop members for transmitting strains therethrough, and a tie strap connecting said draft sills to prevent spreading of same and underlying the key for supporting the latter in its 40 various positions.

In testimony whereof we affix our signatures.
